CATHODE-RAY BEAM DEFLECTING CIRCUIT

Simeon I. Tourshou, Philadelphia, Pa., assignor
to Radio Corporation of America, a corporation
of Delaware

Application March 9, 1946, Serial No. 653,261

13 Claims. (Cl. 315—27)

1

The present invention relates to television systems in which the electron scanning beam of a cathode ray tube is electromagnetically deflected cyclically to effect the reproduction of an image, and more particularly relates to means for overcoming such distortion of the image as results from non-linear deflection of the scanning beam.

Television systems of the above type frequently include a horizontal, or line, deflection circuit in which one or more power output tubes are connected to supply cyclically varying current through a coupling transformer to suitable beam deflection coils which are associated with the cathode ray image producing tube. It is known in such deflection circuits to employ a so-called damper tube, usually a diode or in some instances also a triode, shunted across the beam deflection coils. In such an arrangement, the energy stored in the circuit inductance during the retrace periods of the cathode ray scanning beam causes a current flow through the damper tube during scan. This current theoretically may be combined with the current output of the power tube or tubes to a summation characteristic which is linear with respect to time. The theoretically linear summation current thus produced is that which actually flows through the beam deflection coils thereby to bring about a substantially uniform angular deflection of the cathode ray beam at line-scanning frequency.

It has been found in practice, however, that a damper tube of the nature set forth above does not always completely remove the high-frequency oscillations which occur immediately following retrace, and that these high-frequency oscillations, if present, cause a number of vertical bands, or bars, to appear near one side of the image raster, with resulting distortion of the image in this region. These high-frequency oscillations and the effects thereof may be materially reduced by the use of additional damping means, such as a series resistance-condenser combination, acting in parallel with the damper tube circuit.

The utilization of additional damping means to reduce the high-frequency oscillations which occur following retrace, however, has the effect of lowering the voltage across the beam deflection coils near the end of scan. This is undesirable, since the corresponding reduction in current flow through the deflection coils decreases the beam scanning rate and causes a crowding of the reproduced image near one side of the raster. It has been found that this non-linearity of scan due to a dropping off of deflection coil current

and voltage may be compensated for by controlling the flow of current through the damper tube, and that as a result of such control, the voltage across the beam deflection coils during scan may be maintained relatively constant. As a consequence, substantial linearity of scan is obtained.

One object of the present invention, therefore, is to provide, in a television system in which a cathode ray scanning beam is electromagnetically deflected, means for causing such deflection to occur at a substantially linear rate with respect to time.

Another object of the invention is to provide, in a television system of the nature set forth, means for reducing the amplitude of the high-frequency oscillations which occur following retrace, and additionally to prevent the use of such means from affecting the linearity of scan near the end of the trace portion of each deflection cycle.

A further object of the invention is to provide, in connection with a television circuit of the nature set forth, which includes a damper tube, means whereby the flow of current through such damper tube may be controlled through the application thereto of a voltage which varies as a function of the current output of the power tube, and also to provide means for controllably delaying the phase of this voltage.

Other objects and advantages will be apparent from the following description of a preferred form of the invention and from the drawings, in which:

Fig. 1 is a circuit diagram of a preferred embodiment of the present invention;

Figs. 2 and 3 are sets of waveforms useful in explaining the operation of the circuit of Fig. 1; and

Figs. 4 and 5 are modifications of the circuit of Fig. 1.

Referring first to Fig. 1, there is shown a television deflection and high-voltage rectifier circuit which includes a horizontal power output tube 10. Power tube 10 is adapted to supply, when voltage variations which may have a waveform such as indicated by the reference character 12 are applied to the control electrode thereof, cyclically varying current to a pair of horizontal, or line, cathode ray beam deflection coils 14 through a coupling transformer 16.

Transformer 16 is provided with a primary winding 18, a step-up winding 20 forming in effect an extension of the primary winding 18, and a secondary winding 22. This secondary winding 22 is connected across the horizontal

cathode ray beam deflection coils 14, which, together with a pair of vertical, or field, deflection coils 24 preferably form part of a yoke assembly encircling the neck of a cathode ray image-reproducing tube or kinescope 26. The vertical cathode ray beam deflection coils 24 are energized by sawtooth current of field-scanning frequency from a deflection generator 28, which may be of any suitable design. It will not, therefore, be described in detail.

During operation of the circuit of Fig. 1, as will be later brought out, voltage surges are produced across the primary winding 18 of transformer 16. These voltage surges are stepped up by the winding 20 and applied to a surge-type rectifier 30, which may, for example, be of the type disclosed in a copending U. S. patent application of Otto H. Schade, Serial No. 578,678, filed February 19, 1945, or in a copending U. S. patent application of Albert W. Friend, Serial No. 631,732, filed November 29, 1945. The output of rectifier 30, which is a substantially smooth D. C. potential, is applied to the second anode 32 of the kinescope (cathode ray image producing tube) 26 over conductor 34.

The voltage variations 12 applied to the control electrode of power tube 10, together with its bias potential, produce a rising current in tube 10 during scanion, such as represented by the waveform portion 36 in Fig. 2. This current is cut off at the beginning of retrace time.

The current in the deflection coils 14 and transformer 16 does not disappear at the instant of cut-off of tube 10, however, due to the inherent distributed capacity of the circuit. This distributed capacity, at the instant of the beginning of retrace, is charged to a relatively low voltage.

The inductance of the deflection coils 14 and transformer 16, together with the above-mentioned distributed capacity, forms a tuned circuit in which high-frequency oscillations would normally be produced. These oscillations begin with the start of retrace time, and one-half cycle of the natural period of oscillation of the circuit is represented by the curve portion 38 in Fig. 2. After one-quarter cycle, the current in the deflection coils 14 is reversed, and the oscillation is stopped after one-half cycle near the negative current peak. The means for producing such a result include the series combination of a damper tube 40 and a condenser 42 connected across the secondary winding 22 of transformer 16.

During retrace, that is, during the half-cycle of the natural period of oscillation of the circuit, the current in both tubes 10 and 40 is completely blocked, the voltage as represented by the waveform portion 44 (Fig. 2) reaching a high value at one-quarter cycle when the current passes through zero. In order that linear deflection of the cathode ray beam be produced, it is necessary that the rate of change of the current in the deflection coils 14 be maintained constant during the scanning portion of the deflection cycle, as shown by the solid-line waveform portion 46 in Figure 2, and, as long as this rate of change of current is constant, the voltage across the deflection coils 14 will remain steady at a predetermined level, as represented by the solid-line waveform portion 48.

The polarity of the voltage applied to the anode of the damper tube 40 immediately following retrace is such as to cause the damper tube 40 to conduct. The waveform of the normal current flow through tube 40 may be such as indicated

in Fig. 2 by the solid-line waveform portion 50.

When the damper tube current represented by the curve 50 in Fig. 2 is properly matched with the power tube current represented by the curve 58, the summation of these currents will have a linear characteristic as shown by the solid-line curve portion 46, and hence this curve 46 represents the current actually flowing through the deflection coils 14 during scanion.

It has been found in practice, however, that it is difficult to remove completely the high-frequency oscillations which occur following the retrace portion of each deflection cycle through the use of the damper tube circuit 40, 42 alone, and, as a result, a number of alternate light and dark vertical bands appear near one side of the image raster. To assist the tube 40 in damping out the high-frequency oscillations that cause these vertical bands and consequent image distortion, the condenser 42 is chosen to be of relatively low value, and a resistor 52 is employed in parallel with the damper tube 40. The R-C. combination 52, 42 is thus also shunted across the secondary transformer winding 22, and, together with the damper tube circuit 40, 42, results in substantially complete elimination of the high-frequency oscillations which normally are produced in the manner set forth above.

When condenser 42 is chosen to be of relative low value, however, the voltage appearing across the deflection coils 14 during scanion does not remain constant. Instead, this voltage falls off, as shown by the broken curve portion 54, near the end of the scanning interval. The current through the deflection coils 14 likewise departs from linearity in the manner indicated by the broken curve portion 56.

To overcome the above undesirable effects, the upper plate (in the drawing) of condenser 42 is connected to the upper plate of a further condenser 58 through a variable inductance 60. The lower plates of the two condensers 42 and 58 are joined together. The primary winding 18 of transformer 16 is connected to condenser 58 in such a manner that when the plate current of power tube 10 varies during scanion, as shown by the curve portion 36 in Fig. 2, a varying voltage will be developed across condenser 58. The waveform of this varying voltage may be such as indicated by the reference character 62 in Fig. 3. The positive peak 63 of this voltage waveform 62 occurs substantially at the mid-point in the scanning portion of the deflection cycle.

The voltage thus developed across condenser 58 is applied to condenser 42 through the variable inductance 60. The effect of inductance 60 on the voltage waveform 62 is to delay the occurrence of the positive peak 63 of the wave. The voltage across condenser 42 may, therefore, have a waveform somewhat similar to that represented by the reference character 64, the phase of the positive peak 63 being shifted so as to occur later in the scanning interval.

The current through damper tube 40 normally decreases toward the end of scanion in the manner indicated by the solid waveform portion 50 in Fig. 2. However, as stated above, a voltage which may be such as represented by waveform 64 is applied across condenser 42. Since the upper plate of condenser 42 is directly connected to the cathode of tube 40, the voltage developed across condenser 42 varies the conduction characteristics of tube 40. This variation is such that the current flow through tube 40 decreases at a more rapid rate near the end of the scanning period,

as illustrated by the broken-line curve portion 68 of Fig. 2.

Since the damper tube circuit 40, 42 is in shunt with the deflection coils 14, this reduction in damper tube current as shown by the waveform portion 66 acts to eliminate, by reason of the combination of curves 50 and 36, the non-linear portion 56 from the otherwise linear current curve 46. Such an expedient eliminates the crowding of the reproduced image near one side of the image raster, and, since distortion near the opposite side due to high-frequency oscillations following retrace is materially reduced by the additional damper circuit 52, 42, the reproduced image is left substantially free from these two undesirable features.

The amount by which the instant of occurrence of the positive peak 63 of wave 64 may be delayed is controllable by varying the value of inductance 60. This inductance 60 may be of any suitable type such, for example, as a permeability-tuned inductor. Normally, the value of inductance 60 is selected so as to compensate for the non-linearity of scan introduced through the use of the R-C combination 52, 42, but it may also be selected so as to compensate for non-linearity which would otherwise result from an improper matching of damper tube current and power tube current as shown in Fig. 2. Furthermore, the present invention is useful in overcoming non-linearity which is inherent in wide-angle kinescopes the faces of which are either flat or substantially so. This is due to the fact that movement of the electron scanning beam across the surface of such flat-faced kinescopes is a tangential function of the angular deflection of the beam.

The anode of the power output tube 10 is connected to the B+ terminal in Fig. 1 through a D.C. path which includes the primary winding 18 of transformer 16, the inductance 60, the resistor 52, and the secondary transformer winding 22. As a result of this connection, the voltage developed on the capacitor 42 during operation of the system is of such polarity as to increase, or "boost" the voltage of the power source connected to the said B+ terminal. Accordingly, the energy thus recovered from the secondary circuit may be utilized to obtain greater scanning power in the manner set forth, for example, in a copending United States patent application of Otto H. Schade, Serial No. 593,161, filed May 11, 1945, or in a copending United States patent application of Charles E. Torsch, Serial Number 610,368, filed August 11, 1945. Conversely, the power source connected to the said B+ terminal may be reduced in value by an amount substantially equal to the value of the energy recovered, while maintaining the same scanning output.

In practice it has been found that values of .05 mf. for capacitor 42, .035 mf. for capacitor 58, and 5 to 15 microhenries for inductance 60, are suitable for obtaining the results described. However, these values may be altered to suit various operating conditions and in accordance with the values of the other components of the circuit.

Figs. 4 and 5 show modifications of the circuit of Fig. 1. In Fig. 4 the inductor 60 is of fixed value, and a pair of additional variable inductors 66 and 68 are employed, the inductor 66 being effectively in series with the capacitor 42, as shown, and the inductor 68 being effectively in series with the capacitor 58. Fig. 5 utilizes the adjustable inductor 60 of Fig. 1, but illustrates the manner in which the cathode of damper tube 40 may be connected to a tap on this inductor so

that a portion of the latter is effectively in series with capacitor 42. A second tap 70 on inductor 60 has connected to it the lead from primary winding 18 of transformer 16, so that another portion of the inductor 60 is effectively in series with capacitor 58.

It will be appreciated that the waveforms of the currents and voltages shown in Figs. 2 and 3 are given merely as an aid in understanding the operation of the circuit of Fig. 1, and do not necessarily represent the actual amplitudes or durations of these currents and voltages.

Having thus described my invention, I claim:

1. In a television system in which a power output tube is adapted to deliver cyclically varying current through a coupling transformer to the electromagnetic beam deflection means associated with a cathode ray tube wherein an electron beam is developed and then deflected by the passage of 15 said current through said deflection means so as to scan a target area, and in which means, including a diode, are provided in shunt with said coupling transformer for damping out oscillations which would normally be produced during a 20 portion of each current cycle in part by the inductance of said coupling transformer and said deflection means, the combination of means for deriving a cyclically varying voltage from the 25 cyclically varying current delivered by said power output tube, means for delaying the phase of the 30 said cyclically varying voltage, and means for applying said phase-delayed voltage to the cathode of said diode.
2. A television system in accordance with claim 35 1, in which said phase-delaying means is adjustable to vary the delay interval.
3. A television system in accordance with claim 1, in which said phase-delaying means comprises a permeability-tuned inductor.
4. In a television system employing a cathode ray tube wherein an electron beam is developed and then deflected to scan a luminescent surface, and in which the means for deflecting said electron beam includes means for generating a cyclically varying current, at least one deflection coil associated with said cathode ray tube, means for coupling said generating means to said deflection coil, and means including a two-element electron 45 discharge device for damping out undesired voltage oscillations produced across said deflection coil, the combination of means for developing a voltage which varies as a function of variations in the current output of said generating means, means for altering the waveform of the said developed voltage, and means for applying the voltage the waveform of which has been so altered to one element of the said two-element electron discharge device.
5. A television system in accordance with claim 60 4, in which said waveform-altering means comprises means for delaying the phase of said developed voltage.
6. A television system in accordance with claim 65 4, in which said two-element electron discharge device is a diode, the output of said waveform-altering means being applied to the cathode of said diode.
7. In a television system in which a power output tube is adapted to deliver cyclically varying current through a coupling transformer to a pair of deflection coils associated with a cathode ray tube wherein an electron beam is developed and then deflected by passage of said current through 70 said deflection coils so as to scan a luminescent target, the combination of a damper tube, having

at least an anode and a cathode, and a first condenser connected in series across said pair of deflection coils so as to reduce the amplitude of oscillations which would normally be produced during a portion of each deflection cycle in part by the inductance of said coupling transformer and said deflection coils, a further condenser, means for connecting said further condenser to the primary winding of said coupling transformer so as to develop across said further condenser a voltage which varies as a function of variations in the current flow through said primary winding, an inductor, and means for applying the voltage developed across said further condenser through said inductor to the cathode of said damper tube.

8. A television system according to claim 7, further comprising means for varying the value of said inductor.

9. A television system according to claim 7, further comprising an impedance element connected in parallel relation with said damper tube so as to further reduce the amplitude of said oscillations.

10. In a television system in which a cyclically varying current is generated and delivered to at least one cathode ray beam deflection coil through an inductive coupling member, the combination of a diode and a condenser connected in series across said cathode ray beam deflection coil, the cathode of said diode being connected to one plate of said condenser, an inductor, said one plate of said condenser also being connected to one terminal of said inductor, a further condenser having one plate connected to the other terminal of said inductor, means for connecting the remaining plate of said further condenser to the remaining plate of said first-mentioned condenser, and means for connecting said one plate of said further condenser to a point on said inductive coupling member.

11. In a television system in which a cyclically varying current is generated and delivered to at least one cathode ray beam deflection coil through an inductive coupling member, the combination of 5 a diode, a first inductor, and a first condenser connected in series across said cathode ray beam deflection coil, the cathode of said diode being connected to one terminal of said first inductor, a second inductor having one terminal thereof 10 connected to the cathode of said diode, a third inductor and a second condenser connected in series, the terminal of said third inductor opposite to that which is connected to said second condenser being joined to the remaining terminal of said second inductor, means for joining together the unconnected plates of said first and second condensers, and means for connecting said inductive coupling member to the said remaining terminal of said second inductor.

12. A television system in accordance with claim 11, in which said first and third inductors are each adjustable.

13. In a television system in which a cyclically varying current is generated and delivered to at least one cathode ray beam deflection coil through an inductive coupling member, the combination of a diode having an anode and a cathode, the anode of said diode being connected to one end of said cathode ray beam deflection coil, a first condenser, a second condenser, one plate of each of said condensers being connected to the remaining end of said cathode ray beam deflection coil, an inductor, means for connecting the ends of said inductor between the remaining plates of 25 said first and second condensers, means for connecting the cathode of said diode to a tap on said inductor, and means for connecting said inductive coupling member to a further tap on said inductor.
